(57) CLAIM

I claim the ornamental design for a bed, as shown and described.

DESCRIPTION

FIG. 1 is a perspective view of the bed with the mattress shown in broken lines, the mattress forming no part of the claimed design;

FIG. 2 is a front view thereof; and,

FIG. 3 is side view thereof, the opposite side being a mirror image thereof.

1 Claim, 3 Drawing Sheets
